UNITED STATES PATENT OFFICE.

JOSEPH LEVEEN AND MIFFLIN L. ASHBAUGH, OF ANDERSON, INDIANA.

ELECTRIC CIGAR-LIGHTER.

1,039,553.

Specification of Letters Patent. Patented Sept. 24, 1912.

Application filed February 16, 1912. Serial No. 677,951.

To all whom it may concern:

Be it known that we, JOSEPH LEVEEN and MIFFLIN L. ASHBAUGH, citizens of the United States, residents of Anderson, in the county of Madison and State of Indiana, have made a certain new and useful Invention in Electric Cigar-Lighters; and we declare the following to be a full, clear, and exact description of the same, such as will enable others skilled in the art to which it appertains to make and use the invention, reference being had to the accompanying drawings, and to letters or figures of reference marked thereon, which form a part of this specification.

Figure 1 is a perspective view of the preferred embodiment of the invention. Fig. 2 is a central vertical section of the same. Fig. 3 is a diagrammatic view of the electric circuit. Fig. 4 is a sectional fragmentary detail view of the dip, the wick or absorbent being removed. Figs. 5 and 6 are detail fragmentary views showing the manner of using the dip.

The invention has relation to electrically ignited lighters for cigars, and the like, and it consists in the novel construction and combinations of parts as hereinafter set forth.

In the accompanying drawings illustrating the invention, the numeral 1, designates a dip designed to carry a sufficient amount of alcohol or other liquid hydrocarbon for lighting purposes and 2, is a pair of circuit terminals or contacts of an electrical circuit 3, said contacts being spaced apart and having projections 4, spaced from each other by intervals 5, the lateral surfaces 6 of said projections having presentation outward with relation to the space separating said contacts, and said dip being adapted to be struck in a sliding manner along said lateral surfaces and across said intervals to successively make and break the circuit and cause a succession of sparks to ignite the dip.

It is preferred to interpose a lamp or lamps 7 in said circuit, said lamp to be successively illuminated and extinguished as the circuit is made and broken by said dip, and being located behind a transparency 8, bearing suitable advertising or other matter.

The contacts are preferably provided with a double parallel series of projections 4, as shown, the lateral surfaces 6 of the pro-

jections of the two series being located in 55 converging planes, and it is further preferred to form the dip with a hollow metal stem 9, having a wedge form head 10, provided with openings or slots 11 in its side walls, a wick or absorbent material 12, being located within said head, and back of 60 said openings.

It is preferred to locate the invention within a casing 14 having a base 15 wherein the lamps are located, and an upper smaller 65 part 16, wherein the receptacle 17 for the hydrocarbon is located, said upper part having a slot 18 in its upper wall, and the contacts being secured to the casing along said slot. The base and the upper part of the 70 casing are provided with transparent walls 8, bearing the advertising or other matter.

Owing to the wedge form of the head of the dip, and the converging projections of the contacts, the head is guided between the 75 contacts in its entrance and guided along the contacts to make and break the circuit. The lamp being alternately illuminated and extinguished at the same time that the dip is used, the attention of the user is naturally 80 drawn to the advertising or other matter upon the transparency.

The electric circuit may have binding posts 11^a for the main lead wires 9^a and 10^a. The battery is shown at 12^a, the lamp filament at 85 14^a, and the handle for the dip at 3^a.

Having thus described our invention, what we claim as new and desire to secure by Letters Patent is:

1. An electric cigar lighter, comprising an 90 electric circuit, a dip, a pair of contact plates having downward bent converging serrated edge portions separated by a wedge form interval of greater width at the top than at the bottom thereof, the serrations 95 of said edge portions forming a guideway for sliding movement of the dip in a straight path, the wedge form interval allowing free movement of the dip downward into contact with and upward away from the serrations 100 at the start and finish of the sliding movement.

2. An electric cigar lighter, comprising an 105 electric circuit, a dip, a pair of contact plates having downward bent converging serrated edge portions separated by a wedge form interval of greater width at the top than at the bottom thereof, the serrations

of said edge portions forming a guideway for sliding movement of the dip in a straight path, the wedge form interval allowing free movement of the dip downward into contact with and upward away from the serrations at the start and finish of the sliding movement, said dip having a wedge form head for close contact with said projections.

3. In an electric cigar lighter, a dip having a hollow wedge form head, provided

with lateral openings, and a wick within said head and behind said openings.

In testimony whereof we affix our signatures in presence of two witnesses.

JOSEPH LEVEEN.
MIFFLIN L. ASHBAUGH.
